CLAIM

The ornamental design for a housing for electronic devices, as shown.

DESCRIPTION

FIG. 1 is a photograph from a perspective showing the top, end, and side of a housing embodying the ornamental design of the present invention.

FIG. 2 is a photograph from a perspective showing the top, end, and side of the housing shown in FIG. 1.

FIG. 3 is a photograph from a perspective showing the bottom, end, and side of the housing shown in FIG. 1.

FIG. 4 is a photograph from a perspective showing the top, end, and side of a second form of housing embodying the ornamental design of the present invention.

FIG. 5 is a photograph from a perspective showing the top, end, and side of the housing shown in FIG. 4; and,

FIG. 6 is a photograph from a perspective showing the bottom, end, and side of the housing shown in FIG. 4.
